United States Patent Office

Des. 183,259

Patented July 22, 1958

183,259

CUFF GUARD

John M. Lyles, Kansas City, Mo., assignor of one-third to Phillip P. Scaglia, Kansas City, Mo., and one-third to Harold G. Parrott, Mission, Kans.

Application May 7, 1957, Serial No. 46,056

Term of patent 14 years

(Cl. D17—7)

FIGURE 2.

FIGURE 3.

The broken line showings are for illustrative purposes only.

I claim:

The ornamental design for a cuff guard, as shown and described.
